UNITED STATES PATENT OFFICE.

WILLIAM P. FEST, OF BROOKLYN, NEW YORK.

DESIGN FOR A CARRIAGE-BODY.

SPECIFICATION forming part of Design No. 20,037, dated July 15, 1890.

Application filed June 20, 1890. Serial No. 356,159. Term of patent 14 years.

To all whom it may concern:

Be it known that I, WILLIAM P. FEST, of Brooklyn, county of Kings, and State of New York, have invented a new and original Design for Carriages, of which the following is a specification, reference being had to the accompanying drawing, forming part thereof, which represents a side view of a carriage showing my design.

The leading feature of my design consists in having the lower back quarter panel bounded by a molding curved into ogee form and having a scroll adjacent to the lower rear corner of the door-opening.

a is the lower back quarter panel of the carriage situated to the rear of the door *b*. The rear and lower edges of the panel *a* are bounded by a molding, which is curved in ogee form, as shown, from *c* to *d*, and at *e* forms a scroll. 15 20

What I claim is—

The design for a carriage-body, substantially as shown and described.

WILLIAM P. FEST.
